UNITED STATES PATENT OFFICE.

ROY CHRISTIAN BECK, OF LOS ANGELES, CALIFORNIA, ASSIGNOR TO SELECTASINE SYSTEM, OF SAN FRANCISCO, CALIFORNIA, A CORPORATION OF CALIFORNIA.

METHOD OF AND APPARATUS FOR STENCILING.

Application filed April 19, 1927. Serial No. 184,932.

My invention relates to the art of stenciling and more particularly to the art of stenciling through fabric.

A process of stenciling known to the trade 5 as the "selectasine process" utilizes a stencil comprising a sheet of fabric stretched tightly on a frame and having portions of the fabric rendered impervious to paint, the portions through which paint may pass comprising 10 areas of a design.

A cardboard or other suitable material, upon a surface of which it is desired to paint said design, is laid upon a flat table and the frame is disposed so that the stencil lies flat 15 against the cardboard. Paint in a semi-liquid state is placed upon the stencil at one end and is drawn over the stencil in a wave by a scraper which is preferably a rubber "squeegee". The paint thus drawn over the 20 stencil fills the open pores of the previous design portions of the stencil and adheres to the surface of the cardboard so that when the stencil is raised, the paint is drawn by its adhesion to the cardboard substantially 25 entirely out of the pores of the stencil which it filled.

In raising the stencil, a momentary suction is created between the stencil and the cardboard, thus tending to tear the stencil and 30 slow up the work.

It is an object of my invention to eliminate suction forming as the stencil leaves the cardboard.

Furthermore, in raising the stencil from 35 the work the edges of the stencil tend to leave the work first, being closest to the frame, and the middle portions later. This leaves a moire effect on the work, containing wave forms made by the stencil progressively leaving 40 the work.

It is an object of my invention to provide a method of stenciling in which no such wave marks are left on the work.

Though the selectasine process has come 45 into extensive use in the production of advertising posters and the like, considerable difficulty has been met with in providing means whereby this art may be economically used in large quantity production.

It is an object of my invention to provide 50 a method of and apparatus for stenciling through fabric by which the work may be turned out economically in large quantities.

No fabric has been found for use as a

stencil which will not stretch under the pressure of the squeegee especially toward the end of a stroke. This causes other portions of the stencil than that immediately contacted by the squeegee to "creep" upon and, to some extent, smear the work.

It is a further object of my invention to provide a method of and apparatus for stenciling through fabric which will prevent stretch in the stencil from smearing the work.

Further objects and advantages will be 65 made manifest hereinafter.

In the drawings in which a preferred embodiment of the apparatus of my invention is illustrated,

Fig. 1 is a plan view of my stenciling apparatus.

Fig. 2 is a vertical sectional view taken on the line 2—2 of Fig. 1.

Fig. 3 is a vertical sectional view taken on the line 3—3 of Fig. 2.

Fig. 4 is a fragmentary oblique perspective view illustrating a detail of my stenciling apparatus.

Fig. 5 is a fragmentary enlarged view of a portion of Fig. 2.

Figs. 6 to 10 inclusive are similar views, each of which is taken substantially on the line 6—6 of Fig. 2 and illustrating the paint-feed mechanism of my apparatus.

Referring specifically to the drawings, the apparatus of my invention is indicated by the numeral 10 which, as clearly shown in Figs. 1 and 2, includes a frame 11 having two front legs 12 and two back legs 13 which are connected together in pairs near their lower ends by transverse tie bars 14. Transverse tie bars 15 are superimposed above the tie bars 14 and connect the legs 12 and 13 together at their upper ends. A longitudinal tie bar 16 is formed of angle iron and riveted to the legs 13 on the same level as the tie bars 14 so as to rigidly space the lower ends of the legs 13. A longitudinal tie bar 17, also formed of angle iron, is superimposed above the tie bar 16 and spaces the legs 13 from each other at a point substantially midway between the tie bar 16 and the top of the legs 13. Two pairs of converging arms 18 and 19 are connected to the ends of the tie bars 16 and 17 and converge and connect with each other to form a rigid bearing base plate 20 which is disposed slightly above the level of the longitudinal tie bar 17. Longitudinal

- rails 25 and 26 are preferably formed of angle iron and rest upon and are secured to upper ends of the legs 12 and 13 so that corresponding webs are parallel to each other. The rails 25 and 26 have small upper and lower angle irons 27 and 28 provided upon the opposing faces of the parallel webs of these rails so as to form opposed wheel grooves 29, for a purpose to be described later.
- 10 Sliding bearing blocks 35 and 36 are connected to the rail 26 and the tie bar 16 respectively near the center of the apparatus 10 so as to provide guideways for a vertical plunger rod 37. A treadle 38 has a fulcrum 39 resting upon the floor. One end 40 of the treadle 38 is adapted to be depressed by the operator's foot, and the opposite end 41 of the treadle 38 is pivotally connected to a link 42 which is pivotally connected to the lower end 44 of the plunger rod 37. A bearing block 45 is connected to the rod 37 near the upper end thereof by bolts 46 and 47. The opening in the block 45, through which the bolt 47 passes, is enlarged to permit a limited horizontal movement of the lower end of the block 45 relative to the plunger rod 37.
- 15 A bearing 50 is hingedly mounted upon the plate 20. A shaft 51 extends through and journals in the bearing block 45 and the bearing 50. Mounted on the shaft 51 just behind the block 45 is a circular cam 53 which is secured to the shaft by a set screw 54. The cam 53 has a radial notch 54' extending in from the periphery thereof. A supporting bracket 56 is secured to the upper face of the longitudinal tie bar 17 directly beneath the axis of the shaft 51 so that an upstanding lug 57 of the bracket 56 is adapted to enter the notch 54, when the cam 53 is in the position shown in
- 20 Fig. 3.
- 25 A large spur gear 65 and a work-holding drum 66 are rigidly mounted upon the inner end of the shaft 51, as clearly shown in Fig. 2. A piece of work 67 is in this instance formed of sheet material shaped to form a cylinder which will snugly fit over the drum 66. In Fig. 2 the material of the work 67 is broken away for the purpose of revealing the drum 66. The gear 65 has a pitch diameter which is substantially the same as the diameter of the exterior surface of the work 67.
- 30 When the treadle lever 38 is in the dotted line position 69 in which it is shown in Fig. 2, the shaft 51 and the parts rigidly associated therewith are disposed in the dotted line position 70. When the treadle 38 is depressed into its full line position, the shaft 51 and its rigidly associated parts are raised to the full line position in which they are shown in Fig. 2.
- 35 In Fig. 3 the circular cam 53 is shown in full lines in its downward position which corresponds to the dotted line position 70 of Fig. 2. In order for the cam 53 to thus assume its downward position, the notch 54 must be opposite the lug 57 so that the lug may enter the

notch, as shown in Fig. 3. Likewise, in order that the shaft 51 be rotated in the bearings 45 and 50, the circular cam 53 must be raised so that the lug 57 will be removed from the notch 54. When the cam 53 is thus raised and the shaft 51 rotates so that the notch 54 is moved out of registry with the lug 57, the latter contacts the peripheral surface of the cam 53 so as to support the shaft 51 in elevated position.

40 A stencil screen 75 includes a rectangular wooden frame 76 having side bars 77 which are connected by end bars 78 and 79. A sheet of fabric 80 is stretched tightly over and secured to the lower surface of the frame 76. The frame 76 is adapted to nest in a rectangular frame 85 formed of angle iron. The frame 85 has end members 86 and side members 87 and 88. Axe bars 89 and 90 are secured to the outer faces of the frame members 86, the axe bars extending to each side of the frame 85 and being provided with rollers 91 which extend into the track grooves 29 formed on the inner faces of the rails 25 and 26. The rollers 91 thus support the stencil screen 75 so that this may be easily rolled from end to end of the rails 25 and 26. Actuating posts 92 are provided upon the axe bar 90 to extend upward therefrom, the posts 92 each having a horizontal finger 93 for a purpose to be described later.

45 The side member 88 of the angle iron frame 85 is provided with a rectilinear rack 95, the teeth of which extend downward, the pitch plane of the teeth coinciding with the plane of the screen fabric 80. Near the opposite ends of the rack 95, the metal of the side bar 88 is cut away, as clearly shown in Fig. 4, at 96, for a purpose to be described later. Stops 98 and 99 are provided at opposite ends of the rails 25 so as to limit the longitudinal rolling movement of the screen 75 and prevent the rollers 91 from leaving the track grooves 29.

50 When the screen 75 is in the position in which it is shown in Fig. 1, and the shaft 51 is raised into the full line position in which it is shown in Fig. 2, the upper portion of the spur gear 65 moves through one of the recesses 96 formed in the lower outside corner of the side bar 88 and meshes with the rack 95. When the spur gear 65 is thus in mesh with the rack 95, the external surface of the work 67 just comes into contact with the lower surface of the screen fabric 80. If the screen 75 is now moved longitudinally on the rails 25 and 26, the spur gear 65 is rotated, causing the work 67 to make a rolling contact with the lower surface of the screen fabric 80 and also causing the circular cam 53 to rotate, thus moving the notch 54 out of registry with the lug 57 and causing the shaft 51 to be maintained in elevated position until a complete revolution thereof has been completed. Such a revolution is completed when the screen 75 is disposed at the opposite ends of the rails

25 and 26 from that at which it is disposed in Fig. 1. When this revolution of the shaft 51 is completed, the notch 54 again comes into registry with the lug 57, permitting the shaft to drop down so that it is locked against rotation. It may be clearly seen that a line contact is made between the work 67 and the lower surface of the fabric 80 on a vertical plane passing through the axis of the shaft 51. In carrying out the method of my invention it is necessary that paint be forced through the screen fabric 80 substantially on the line of contact between this fabric and the work 67.

In order to accomplish this I have provided a paint-feed mechanism 100, the structure and operation of which is clearly illustrated in Figs. 5 to 10 inclusive. Standards 101 and 102 are mounted on the rails 26 and 25 respectively to extend upward therefrom, a shaft 103 being horizontally journaled in these standards. Adjustment screws 104 and 105 are threadedly mounted upon the standard 101 for a purpose to be described later. The paint-feed mechanism 100 includes a scraper body 108 which extends parallel with the shaft 103 and which has arms 109 and 110 which receive the shaft 103 so that the mechanism 100 is rotatably mounted upon the shaft 103. The arm 109 has a lug 110^a provided with a friction foot 111 which is disposed in engagement with an upper surface of the rack 95. The arm 109 is disposed between the ends of the screws 104 and 105 so that these screws limit the rotation of the mechanism 100 about the shaft 103. A rubber scraper or squeegee 113 is provided in the lower part of the scraper body 108, and slide rods 114 extend substantially horizontally from the body 108 on opposite sides of the center thereof.

A paint pan 115 has a vertical wall 116 and a floor 117, the wall 116 being provided with suitable collars 118 which slide upon the rods 114. Springs 119 are disposed about the rods 114 between the scraper body 108 and the wall 116 so as to urge the pan 115 away from the scraper body 108. A detent mechanism 120 is provided upon each of the collars 118 and is adapted to engage with shoulders formed upon the slide rods 114 by annular grooves 122 and 123 thereof. Each detent mechanism 120 has a lever arm 125, the depression of which disengages the detent mechanism from one of the grooves 122 or 123. Pins 126 provided near the ends of the slide rods 114 prevent removal of the collars 118 from the ends of the rods 114. A paint feeder 130 is rigidly secured upon the scraper body 108 so as to project toward the pan 115 and so that a horizontal blade 131 of the paint feeder 130 lies just above the level of the upper surface of the floor 117 of the paint pan 115.

As clearly shown in Fig. 6, the squeegee

113 normally contacts the upper surface of the screen fabric 80 along the line of contact between the screen 80 and the work 67.

The operation of the paint-feeding mechanism 100 is as follows:

Fig. 6 illustrates the screen 75 moving in the direction of the arrow 140 and nearing the end of its stenciling stroke. A wave of paint 141 is disposed in advance of the squeegee 113 so that paint is forced through the previous portions of the screen fabric 80 to apply the design of the stencil screen 75 to the surface of the work 67. The parts of the paint-feeding mechanism 100 maintain the same positions relative to each other during the entire stenciling stroke until the end bar 79 contacts the vertical wall 116 of the paint pan 115, as shown in Fig. 6. Then, as the stencil screen 75 completes its movement in the direction of the arrow 140, the pan 115 is slid along the rods 114 to a paint-retaining position in which it is shown in Fig. 7. Here the screen 75 is at the end of its stenciling stroke and the detent mechanism 120 drops into the annular groove 122 so as to retain the pan 115 in this position. As the pan moves to its paint-retaining position, the paint-feeder blade 131 extends upward into the pan 115 and the squeegee 113 rolls the paint 141 onto the floor 117 of the paint pan 115. Thus when the stencil 75 terminates its stenciling stroke, the paint has been entirely scraped from the fabric 80 onto the floor 117, and the detent mechanism 120 has locked the pan 115 in paint-retaining relation with the squeegee 113. At this time the shaft 51 has been rotated by the gear 65 so that the notch 54 of the circular cam 53 again registers with the lug 57 so that the shaft 51 and the parts assembled therewith, including the work 67, drop downward into the dotted line position 70 of Fig. 2. The work 67 is thus removed from contact with the screen fabric 80 and may be easily drawn from the drum 66 and replaced by a fresh piece of work.

The screen 75 is now moved in the reverse direction as shown by the arrow 143 in Fig. 8. This movement causes the friction foot 111 of the scraper body lug 110^a to rotate the feeding mechanism 100 about the shaft 103 until the arm 109 contacts the screw 105, as shown in Fig. 8. This raises the mechanism 100 from contact with the screen fabric 80 while the stencil 75 is moved a complete return stroke in the direction of the arrow 143. The screen 75, as shown in the drawings, is reciprocated manually in the stencil machine 10, but any suitable power means may be provided to accomplish this.

Fig. 9 shows the screen 75 approaching the end of its return stroke in the direction of the arrow 143 and shows the finger 93 contacting the lever arm 125 of the detent mechanism 120. This results in the release of the detent mechanism so that the spring 119 re-

- turns the pan 115 to its outer position in which it is shown in Fig. 10. As the pan 115 is thus projected outward, the feeder blade 131 scrapes a portion of the paint 141 off onto the screen fabric 80. A new piece of work 67 has by this time been placed upon the drum 66 and by operation of the treadle 38 the new piece of work 67 is raised into contact with the screen fabric 80 and 10 the screen 75 is again drawn in the direction of the arrow 140. As the screen is thus drawn, the paint which was scraped from the pan 115 onto the screen fabric is drawn over the surface of the fabric by the squeegee 113 15 so as to stencil the outer face of the new piece of work 67 in the manner previously described. It will thus be seen that no attention need be given to the paint-feeding mechanism 100 except to maintain a supply 20 of paint upon the pan 115. The height of the feeding blade 131 is just sufficient to remove a slightly greater amount of paint from the pan 115 than that needed for a single stenciling stroke.
- 25 While the work 67 is shown as permanently curved into a cylindrical form, it may be normally flat and be given a curved form merely for the purpose of causing it to contact the screen fabric 80 on a single line. 30 There is a certain amount of "creep" in the screen fabric 80 which would cause a slight smearing were the work 67 to contact the screen fabric over an area which has previously been passed over by the squeegee 113 35 in a stenciling stroke. The line contact utilized in the operation of the stenciling machine 10 therefore substantially prevents this smearing even though there is a certain amount of creep in the stencil fabric 80.
- 40 While I have shown but a single apparatus for carrying out the novel method of my invention it is obvious that this method could be carried out advantageously by a great number of different forms of apparatus. I 45 therefore do not intend my process to be limited to its use with any special apparatus, but have indicated the scope of this process in the following claims.
- I claim as my invention:
- 50 1. A method of stenciling through fabric, which comprises: stretching said fabric in a plane; forming stencils thereon; passing a curved surface of the work into contact with said fabric on a given line; forcing coloring 55 matter through said stencils onto said work at said line; and moving said work relative to said fabric so that said line of contact, between said work and said fabric, moves.
2. A method of stenciling with a substantially flat fabric stencil, which comprises: bringing the work into contact with said stencil; moving said work and said fabric so that contact is maintained therebetween; disposing pigment on said fabric; and causing said 65 pigment to be moved over the surface of said

fabric by forcing a stationary scraper into contact with said fabric on a line on which said fabric contacts said work.

3. A method of stenciling with a fabric stencil, which comprises: disposing said stencil in a flat plane; forming the work so that only a portion of the work may touch the stencil at a time; moving said work relative to said stencil so that various portions of the work successively contact the stencil; and directing pigment through said stencil in the area thereof contacted by said work. 70

4. A method of stenciling with a fabric stencil, which comprises: disposing said stencil in a flat plane; forming the work so that only a portion of the work may touch the stencil at a time; moving said work relative to said stencil so that various portions of the work successively contact the stencil; and positioning a stationary scraper in contact with said stencil opposite the position at which said stencil is touched by the work in order to direct pigment through said stencil upon said work. 80

5. A method of stenciling with a fabric stencil, which comprises: disposing said stencil in a flat plane; forming the work so it is adapted to make a substantially rolling contact with said stencil; moving said work in rolling contact with said stencil; and directing pigment through said stencil in the area thereof contacted by said work. 90

6. A method of stenciling with a fabric stencil, which comprises: disposing said stencil in a flat plane; forming the work so it is adapted to make a substantially rolling contact with said stencil; moving said work in rolling contact with said stencil; and positioning a stationary scraper in contact with said stencil opposite the position at which said stencil is touched by the work in order to direct pigment through said stencil upon said work. 100

7. An apparatus for stenciling, which comprises: a stencil; means for disposing said stencil in a flat plane; means for moving said stencil longitudinally; means for disposing the work in substantially rolling contact with said stencil as said stencil moves longitudinally; and means for directing pigment through said stencil upon said work at the position of said rolling contact. 110

8. An apparatus for stenciling, which comprises: a stencil; means for disposing said stencil in a flat plane; means for moving said stencil longitudinally; means for supporting the work out of contact with said stencil; means for moving the work into contact with said stencil in rolling relation therewith; means connecting said stencil and said work whereby said work makes a rolling contact with said stencil when said stencil is moved longitudinally; and means for directing pigment through said stencil upon said work at the position of said rolling contact. 120

9. An apparatus for stenciling, which comprises: a stencil; means for disposing said stencil in a flat plane; means for moving said stencil longitudinally; means for supporting the work out of contact with said stencil; means for moving the work into contact with said stencil in rolling relation therewith; means connecting said stencil and said work whereby said work makes a rolling contact with said stencil when said stencil is moved

longitudinally; means for directing pigment through said stencil upon said work at the position of said rolling contact; and means for disengaging said connecting means when said rolling contact has continued a desired distance.

In testimony whereof, I have hereunto set my hand at Los Angeles, California, this 14th day of April, 1927.

ROY CHRISTIAN BECK.
